ATTORNEY

UNITED STATES PATENT OFFICE.

THOMAS WOZNY, OF GRAHAM, WASHINGTON.

HORSESHOE.

Application filed October 18, 1921. Serial No. 508,424.

To all whom it may concern:

Be it known that I, THOMAS WOZNY, a citizen of the United States, residing at Graham, in the county of Pierce and State 5 of Washington, have invented new and useful Improvements in Horseshoes, of which the following is a specification.

This invention relates to a horseshoe, the general object of the invention being to provide a shoe which can be easily and quickly placed on a horse's hoof or removed therefrom.

Another object of the invention is to attach a boot to the shoe with means for 10 strapping the boot to the horse's foot.

A further object of the invention is to provide removable calks on the shoe.

This invention also consists in certain other features of construction and in the 20 combination and arrangement of the several parts, to be hereinafter fully described, illustrated in the accompanying drawings, and specifically pointed out in the appended claims.

In describing my invention in detail, reference will be had to the accompanying drawings wherein like characters denote like or corresponding parts throughout the 25 several views, and in which:—

Figure 1 is a side view of the invention,

Fig. 2 is a front view,

Fig. 3 is a plan view,

Fig. 4 is a rear view with parts broken away,

Fig. 5 is a sectional view, and

Figs. 6 and 7 are detail views of the calks in position.

In these views 1 indicates the shoe to which the boot 2 is secured. This boot consists of the lower part 3 formed of metal and the upper part 4 formed of canvas, rubber, or the like. These parts are suitably secured together and the metal part is formed of two portions which are connected together by the screws 5. A bottom piece 6 extends over the shoe and forms a bottom for the boot. This plate and the boot are secured to the shoe by nails, screws, or the like. A flap 7 is also provided at the rear of the boot, this flap being secured to a metal strip 8 which is pivotally secured to the heel portions of the shoe, as shown at 9.

This flap 7 is adapted to fill the space between the adjacent edges of the boot and the boot is held around the horse's foot by means of the straps 10.

Calks 11 and 11' are removably secured to the bottom of the shoe, the toe calks 11' being placed side by side and connected together by the screw 12.

From the above it will be seen that the shoe can be easily and quickly attached to the horse's hoof by the boot and that this boot will protect the hoof and fetlocks. The metal portions of the boot are made of 65 spring metal so that they will grip the hoof when placed thereon.

It is thought from the foregoing description that the advantages and novel features of my invention will be readily apparent. 70

I desire it to be understood that I may make changes in the construction and in the combination and arrangement of the several parts, provided that such changes fall within the scope of the appended claims. 75

What I claim is:—

1. A shoe of the class described comprising a shoe, a boot connected therewith comprising a lower metal part and an upper flexible part, means for strapping the flexible part around the horse's foot, and a flap pivotally secured to the heel part of the shoe and extending between the adjacent edges of the boot.

2. A shoe of the class described comprising a shoe part, a boot secured thereto and consisting of a lower metal part and an upper flexible part, buckle-carrying straps secured to said boot at the rear thereof, a tongue for the boot pivotally secured to the heel part of the shoe, and calks detachably connected with the bottom of the shoe.

3. A shoe of the class described comprising a shoe part, a boot secured thereto and consisting of a lower metal part and an upper flexible part, buckle-carrying straps secured to said boot at the rear thereof, a tongue for the boot pivotally secured to the heel part of the shoe, and calks detachably connected with the bottom of the shoe, the toe calks 100 being placed side by side and connected together.

In testimony whereof I affix my signature.
THOMAS WOZNY.
